UNITED STATES PATENT OFFICE

AUSTIN YOUNG HOY, OF LONDON, ENGLAND, ASSIGNOR TO SULLIVAN MACHINERY COMPANY, OF CHICAGO, ILLINOIS, A CORPORATION OF MASSACHUSETTS

MINING MACHINE

Application filed April 7, 1930, Serial No. 442,313, and in Great Britain August 7, 1929.

This invention is for improvements in or relating to mining machines (more particularly to long-wall mining machines) of the type comprising a main section containing 5 the power unit and a jib which is mounted on the main section for swinging movement in a horizontal plane and has an endless chain, carrying picks or cutters mounted thereon, and adapted to be traversed round 10 the margin of the jib which is formed with a channel to receive and guide the cutter chain. In order to provide chain adjustment in the above type of machine it is usual to mount the jib slidably upon a jib hanger 15 which is pivoted to the main section, the relative adjustment of jib and hanger being controlled by a screw.

It has previously been proposed to make the jib of built-up box-section, comprising 20 in the main, two longitudinal beams spaced apart horizontally and joined top and bottom by plates, the chain channel being formed by four gibs or narrow plates riveted above and below the longitudinal beams aforesaid and 25 projecting beyond their outer edges. The wearing faces of the chain channel, that is to say, the inner faces of the gibs and the outer faces of the longitudinal beams have been made renewable by means of thin metal lining plates, the channel itself being T-shaped with the cross bar of the T inwards and lying vertically. Such constructions have the advantage that all wearing surfaces are renewable, but they are undoubtedly expensive to 30 construct and one object of this invention is to provide a jib of more robust construction and less expensive to manufacture than heretofore. Another object is to provide a jib 35 of such a construction that the cutter-chain channel may be easily machined and that wear at the bearing surfaces may readily be taken up when required.

This invention accordingly provides in or 40 for a mining machine of the type described a jib which is constructed in two longitudinal sections riveted or otherwise joined together with the joint face lying in a horizontal plane through the cutter-chain channel. Preferably, the two longitudinal sections of the jib 45 are substantially identical, the joint face be-

ing central within the cutter-chain channel. Such a construction permits, (where the jib is made for example of cast steel) one pattern being used both for the top and bottom sections.

In addition to the feature of interchangeability of patterns and castings, the construction of the jibs with the joint face central within the cutter-chain channel ensures that each section of the jib is sufficiently robust 55 not to give rise to excessive warping during cooling after casting, this point is of particular importance in casting steel, of which material the jib is preferably made.

According to a further feature of the invention shims are located between the joint faces of the two jib sections, so that wear at the bearing surfaces of the cutter-chain channel may be easily taken up by separating the sections and removing shims.

One construction according to this invention will now be described in detail by way of example with reference to the accompanying drawings, in which

Figure 1 is a plan view of the jib according to this invention, mounted upon a hanger.

Figure 2 is a section upon an enlarged scale taken on the line 2-2 in Figure 1,

Figure 3 is a section upon an enlarged scale taken on the line 3-3 in Figure 1,

Figures 4 and 5 are sections also upon an enlarged scale on the lines 4-4 and 5-5 respectively in Figure 1, and

Figure 6 is a plan view on a reduced scale of a complete mining machine of the type to which a jib according to this invention is applicable.

Throughout this description like reference numerals indicate like parts.

The jib, which is indicated generally by the 80 numeral 10 in Figure 6, comprises a top section 11 and a bottom section 12, which sections are interchangeable and are made of cast steel. These sections are riveted together as at 13, forming a stiff box-section, and the 85 jib is slidably mounted at its inner end upon a hanger 14, which hanger is pivoted for swinging movement as indicated by the dotted line in Figure 6 upon the body portion 15 of the mining machine. The cutting of coal 90

or other material is performed by a series of cutters which are mounted upon an endless chain, indicated generally by the number 16, which travels around the periphery of the jib. The links of the chain, which are not shown, run within a T-shaped cutter-chain channel 17 one half of which is formed in each portion 11 and 12 of the jib.

The construction of the jib in two halves 10 permits the wearing surfaces of the T-shaped channel, and particularly the cross bar 18 of the T which is engaged by projections upon the links of the cutter-chain, to be machined with comparative ease, and without any expensive machine-tool layout. Local contact faces between the two sections of the jib are provided at suitable intervals, the rivets 13 passing through these contacting faces. If desired thin shims, which are indicated at 19, 20 may be placed between the contacting faces to provide for adjustment of the width of the T-shaped channel 17 when wear takes place. Alternatively the shims may be omitted and adjustment provided by machining or scraping down the contacting faces. It will be observed that the joint face between the two sections of the jib is central within the cutter-chain channel.

In order to take up slack in the cutter chain 30 the jib 10 is slidably mounted upon the hanger 14 and the adjustment is effected in the following manner:

Clamped between the two halves 11 and 12 of the jib are two bearing blocks 20 and 21 35 each provided with a semi-circular channel, the two blocks embracing the shank of an adjusting screw 22. Axial movement of this adjusting screw with respect to the jib is prevented by a collar 23 and the head 24 of the 40 screw. The head is pierced with two holes at right angles to each other to take a tommy bar and lies within an aperture 25 pierced completely through both sections of the jib. The end of the screw 22 is threaded and engages a screwed member 26 which is rigidly 45 fixed, for example by means of pins, within a cylindrical bore in the hanger.

In some known construction of jibs it has 50 hitherto been proposed to run the cutter chain over an idler sprocket at the free end of the jib.

In order to provide a cheaper construction it is preferred in a jib according to the present invention to dispense with this idler sprocket, and to run the cutter chain around a semi-circular bearing machined in the free end of the jib. In such a construction it is necessary to make the cross bar 18 of the 55 T-shaped channel 17 deeper around and in the neighbourhood of this semi-circular bearing than along the straight sides of the jib.

This is done in order to accommodate the throw of those projections upon the links of the cutter chain which engage in the cross

bar 18. If desired, however, the usual construction of idler sprocket may be retained.

While there is in this application specifically described one form which the invention may assume in practice, it will be understood that this form of the same is shown for purposes of illustration and that the invention may be modified and embodied in various other forms without departing from its spirit or the scope of the appended claims. 75

I claim:

1. In a mining machine of the type described, a jib which is slidably mounted upon a support for adjusting the cutter chain, having a cutter-chain channel around its periphery and comprising two longitudinal sections with the joint face between them lying in a horizontal plane through the cutter chain channel, and removable shims interposed between the two sections, said sections each having a guideway adapted for slidable attachment to the support. 80

2. In a mining machine of the type described, a jib which is slidably mounted upon a support for adjusting the cutter chain, comprising two identical longitudinal sections with the division between them substantially horizontal, a cutter chain channel extending along two opposed sides and in arcuate form around one end of the jib, 90 the bearing surfaces of which channel are formed in the two sections of the jib, and removable shims interposed between the two sections at the division, said sections each having a guideway adapted for slidable attachment to the support. 95

3. A mining machine cutter bar which is slidably mounted upon a support for adjusting the cutter chain, comprising a pair of symmetrical members disposed in face to face relationship to form the main body of the bar, said members having elongated parallel grooves at their opposite sides and communicating arcuate end grooves, said grooves when said members are united forming a cutter chain guiding channel extending along the sides and completely around the tip end of said bar and said members each having a guideway adapted for slidable attachment to the support. 100 110

4. A mining machine cutter bar which is slidably mounted upon a hanger support for adjusting the cutter chain, comprising a pair of symmetrical members disposed in face to face relationship to form the main body of the bar, said members having elongated parallel grooves at their opposite sides and communicating arcuate end grooves, said grooves when said members are united forming a cutter chain guiding channel extending along the sides and completely around the tip end of said bar, and each symmetrical member having a guide for reception in guideways on the hanger support. 120 125

5. A mining machine cutter bar which is slidably mounted upon a support for adjust-

- ing the cutter chain, comprising a pair of symmetrical members forming the main body of the bar, said members having elongated parallel grooves at their opposite sides and communicating arcuate end grooves, said grooves when said members are united forming a cutter chain guiding channel extending along the sides and completely around the tip end of said bar, said symmetrical members having joint faces lying in a plane midway between the outside plane surfaces of said members and said members each having a guideway adapted for slidable attachment to the support. 10
6. A mining machine cutter bar which is slidably mounted upon a support for adjusting the cutter chain, comprising a pair of symmetrical members disposed in a face to face relationship to form the main body of the bar, said members having elongated parallel grooves at their opposite sides and communicating arcuate end grooves, said grooves when said members are united forming a cutter chain guiding channel extending along the sides and completely around the tip end of said bar, and means for effecting adjustment of said symmetrical members relative to each other to vary the width of said cutter chain guiding channel and said members each having a guideway adapted for slidable attachment to the support. 20
7. A mining machine cutter bar which is slidably mounted upon a support for adjusting the cutter chain, comprising a pair of symmetrical members disposed in a face to face relationship to form the main body of the bar, said members having elongated parallel grooves at their opposite sides and communicating arcuate end grooves, said grooves when said members are united forming a cutter chain guiding channel extending along the sides and completely around the tip end of said bar, said symmetrical members having elongated parallel sides and a curved end, said sections having plane surfaces forming the top and bottom surfaces of the bar and joined together in a plane parallel to said surfaces and midway therebetween, said sections each having a groove extending along its sides and completely around the curved end, said grooves when said sections are united forming a cutter chain guiding channel and said sections each having a guideway adapted for slidable attachment to the support. 30
8. A mining machine cutter bar comprising a pair of symmetrical members disposed in face to face relationship to form the main body of the bar, said members each having a portion to cooperate with a hanger support, a hanger support, and means for effecting adjustment of said members relative to said hanger support. 40
9. A mining machine cutter bar comprising a pair of symmetrical members disposed in face to face relationship to form the main body of the bar, said members having elongated parallel grooves at their opposite sides and communicating arcuate end grooves, said grooves when said members are united forming a cutter chain guiding channel extending along the sides and completely around the tip end of said bar, said symmetrical members having a portion disposed at the end remote from said tip end of the bar to cooperate with a hanger support, a hanger support, and means between said members and said hanger support for effecting adjustment of said members relative thereto. 50
10. A mining machine cutter bar which is slidably mounted upon a support for adjusting the cutter chain, comprising two major sections forming the main body of the bar and having elongated parallel sides and a curved end, said sections having plane surfaces forming the top and bottom surfaces of the bar and joined together in a plane parallel to said surfaces and midway therebetween, said sections each having a groove extending along its sides and completely around the curved end, said grooves when said sections are united forming a cutter chain guiding channel and said sections each having a guideway adapted for slidable attachment to the support. 60
11. A mining machine cutter bar comprising two major sections forming the main body of the bar and having elongated parallel sides and a curved end and communicating openings, said sections having plane surfaces forming the top and bottom surfaces of the bar and having faces contacting in a plane parallel to and midway between said surfaces, a hanger support, and means for effecting movement of said sections longitudinally relative to said hanger support comprising manually operable means including an element receivable in the openings in said sections. 70
12. A mining machine cutter bar comprising two major sections forming the main body of the bar and having elongated parallel sides and a curved end and communicating openings, said sections having plane surfaces forming the top and bottom surfaces of the bar and having faces contacting in a plane parallel to and midway between said surfaces, said sections having elongated parallel grooves at their opposite sides and communicating arcuate end grooves, said grooves when said sections are united forming a cutter chain guiding channel extending along the sides and completely around the tip end of said bar, a hanger support, and means for effecting movement of said sections longitudinally relative to said hanger support comprising manually operable means including an element receivable in the openings in said sections. 80
13. A cutter bar which is slidably mounted upon a hanger for adjusting the cutter chain characterized in that the slidable cutter bar consists of two identical cast steel sections which are joined together in the central horizontal plane through the cutter chain. 90

14. A cutter bar constructed in accordance with claim 13 wherein means including an adjusting screw is provided for adjusting the bar relative to the hanger and the two sections form the bearing for the head of the 5 adjusting screw.

15. A cutter bar constructed in accordance with claim 13 wherein the wear at the bearing surfaces of the cutter chain is taken up by 10 exchanging interpositions between the sections.

In testimony whereof I affix my signature.
